UNITED STATES PATENT OFFICE.

JOSEPH MAST, OF MIAMI, ARIZONA.

POCKET MATCH-SAFE.

1,091,070.

Specification of Letters Patent. Patented Mar. 24, 1914.

Application filed July 28, 1913. Serial No. 781,702.

To all whom it may concern:

Be it known that I, JOSEPH MAST, a citizen of the United States, residing at Miami, in the county of Gila and State of Arizona, have invented certain new and useful Improvements in Pocket Match-Safes; and I do declare the following to be a full, clear, and exact description of the invention, such as will enable others skilled in the art to 10 which it appertains to make and use the same.

This invention relates to special receptacles and packages, and more especially to match safes; and the object of the same is 15 to provide a pocket match safe which serves as a wind guard to prevent the blowing out of the match while lighting a cigar or cigarette.

A further object is to provide a match 20 safe of this character with an annular match chamber or receptacle, and with a removable top.

With these ends in view, the invention 25 consists in the specific details of construction hereinafter more fully described and claimed, and as shown in the drawings wherein—

Figure 1 is a side elevation of this device 30 in closed position ready for insertion into the pocket; Fig. 2 is a central vertical sectional view thereof, showing a match in the act of igniting a cigar; Fig. 3 is a cross section on the line 3—3 of Fig. 2; and Fig. 4 is a detail of the closure.

In the drawings the numeral 1 designates 35 the outer wall or casing of this match safe, which is of metal and preferably tubular, and the numeral 2 designates a band secured within its open upper end or mouth 3 so as to form an exterior shoulder 4. The 40 numeral 5 designates the inner wall or barrel, also made of a short piece of metal tubing co-axial with the casing 1 and connected at its lower end thereto by means of 45 an annular metallic ring forming the lower end 6 of the receptacle. This leaves an annular match chamber 7 between the two walls, closed at its lower end and open at its upper end; and a tubular bore 8 throughout 50 the length of the inner wall or barrel 3.

The closure for this device comprises a short tube section 10, preferably of the same

size and material as the casing 1, and adapted to rest at its lower end around the band 2 and upon the shoulder 4; and a funnel 11 55 whose larger upper end is connected with the upper end of the tube section 10 and whose smaller lower end projects down into the upper end of the bore 8 of the barrel 5 and is slotted so as to produce tongues 12 60 which are sprung outward slightly as best seen in Fig. 4, the wall of this funnel resting on the upper end of the barrel as at 13 when the parts are assembled as best seen in Fig. 2. Any suitable cover 14 may be 65 provided for the upper end of the closure, or, in fact, the cover might be omitted if desired. However, I have shown it as pivoted at 15 to one side of the funnel and having a knob 16 at the other side. When the cover 70 is closed and the closure in place, this end of the entire device is sealed to the entrance of dust or the escape of matches; and the lower end 6 closes the other end of the device except for the open lower end of the barrel 75 5. Through both walls at registering points on one side of the device are perforations 16, and these walls are connected on either side of the series of perforations by radial walls 17 as best seen in Fig. 3.

All parts of the device are by preference 80 of metal, although it is intended that the bore 8 of the barrel 5 shall be lined with asbestos as at 19. The size, proportion of parts and the finish, as well as the optional 85 cover and its manner of mounting, may be left entirely to the manufacturer.

In use, the closure is removed and the annular chamber 7 filled with matches as seen in dotted lines in Figs. 1 and 3, care being 90 taken to put no match between the radial walls 17. I would advise even that the heads of the matches be placed downward as shown in Fig. 2. The closure is then restored to position, and the cover 14 closed, if a cover 95 be used. The article can now be carried with safety in the pocket.

While I have spoken of the walls as concentric and preferably cylindric, it is quite possible that they could be of other contour 100 as will be understood.

When now the user desires to light a cigar or cigarette, he removes the closure from the body, withdraws a match from the cham-

ber 7, restores the closure and turns aside its cover as shown in Fig. 1, inserts his cigar or cigarette C in the lower end of the bore 5, and forces the head of the match M into the 5 funnel 11 and through the tongues 12 at the small end thereof. This ignites the match as it passes said spring tongues, and the flame burns within the bore 8 as the perforations 16 permit, the flame of course coming 10 in contact with the end of the cigar or cigarette as indicated, so that a light is effected.

It will be found possible to light a cigar with this device while the wind is blowing 15 quite a breeze, or while the user is traveling rapidly as in an automobile, and by experiment I have discovered that one can light a cigar in the dark without being seen. So that my improved match safe is useful in 20 times of bad weather, when the user is riding in an automobile or carriage, or at times when it may be that he would not care to be discovered striking a match.

Having effected a light, the burnt out 25 match is withdrawn from the funnel and thrown aside and the cover 14 turned to its closed position so that the device stands as shown in Fig. 1 and can be restored to the pocket.

It is of course quite possible to build this 30 device without the annular chamber for matches and carry the latter elsewhere; this feature need not be amplified, nor need I more than suggest that the device might be 35 provided with a cigar cutter and with other attachments and details which form no part of the present invention. In any event the tubular bore 8 is useful in another way. That is to say, it often occurs that cigar 40 smokers are forced to enter a place (such as a street car) where smoking is not permitted. Assuming that the cigar is a good one and has just been lighted, I find that it is quite possible for the user to take the device 45 from his pocket and slip it over the end of the cigar so that the light thereof passes into the bore 8 within the asbestos lining 19, and the entire article with the cigar in it is then replaced in the pocket, after which in 50 time the cigar goes out and the clothing will not be injured. For this purpose I would make the size of the bore sufficient to contain the ordinary cigar, although obviously my improved match safe might be made in another 55 smaller size for cigarettes and the like.

What is claimed as new is:

1. In a match safe of the class described, the combination with outer and inner concentric walls having registering perforations 60 along one side, radial walls at opposite sides of the series of perforations, and a ring connecting the lower ends of said walls and leaving an annular match chamber between them; of a movable closure for the upper 65 end of said chamber and for the bore

throughout the inner wall, such closure having a match-entrance opening, and means around the opening for igniting the match.

2. In a match safe of the class described, the combination with outer and inner walls having registering perforations along one side, radial walls at opposite sides of the series of perforations, and a ring connecting the lower ends of said walls and leaving an annular match chamber between them; of a band around inside the open mouth of the outer wall and projecting above the same so as to produce a shoulder, a closure consisting of a tube-section adapted to surround the projecting end of said band, and a funnel whose larger upper end is connected with the upper end of said section and whose smaller lower end is slotted into spring fingers for the purpose described, its body when in place resting on the upper end of 85 said inner wall, for the purpose set forth.

3. In a match safe of the class described, the combination with outer and inner walls having registering perforations along one side, radial walls at opposite sides of the series of perforations, and a ring connecting the lower ends of said walls and leaving an annular match chamber between them; of a band around inside the open mouth of the outer wall and projecting above the same so as to produce a shoulder, a closure consisting of a tube-section adapted to surround the projecting end of said band and a funnel whose larger upper end is connected with the upper end of said section and whose smaller lower end is slotted into spring fingers for the purpose described, its body when in place resting on the upper end of 100 said inner wall, and a cover for said closure movably connected at one side to the upper end of said funnel and detachably connected at the other side to the opposite side of the funnel, the cover being bodily removable with the closure.

4. A match safe of the class described 110 comprising outer and inner walls forming an annular match-chamber between them, a lower end wall closing said chamber, asbestos lining within the bore of the inner wall, both walls being perforated along one side, 115 radial walls connecting the walls on opposite sides of said perforations, and a closure for the upper end of the device including a tube section adapted to detachably engage the upper end of the outer wall and a funnel carried by said tube section and adapted to rest on the upper end of the inner wall, the mouth of the funnel being slotted into fingers, for the purpose set forth.

5. A match safe of the class described 125 comprising outer and inner walls forming an annular chamber between them, asbestos lining within the bore of the inner wall, both walls being perforated along one side, and a closure for the upper end of the device in- 130

cluding a tube section adapted to detachably engage the upper end of the outer wall and a funnel carried by said tube section and adapted to rest on the upper end of the inner wall, the mouth of the funnel being slitted into fingers, for the purpose set forth.

In testimony whereof I have hereunto set

my hand in presence of two subscribing witnesses.

JOSEPH MAST.
